ARCHERY BOW

Fred B. Bear, Grayling, Mich., assignor to Bear Archery Company, Grayling, Mich., a corporation of Michigan

Application August 13, 1956, Serial No. 603,592

11 Claims. (Cl. 124—23)

This invention relates to archery bows of the type disclosed in my copending application Serial No. 603,591, filed on even date herewith, in which the loops at the ends of the bow string are replaced by heads fitting into recesses in the ends of the bow. Objects of the present invention are to facilitate bracing and unbracing in bows of this type.

According to the present invention the bow is provided with means to eject one of the heads from its recess in unbracing the bow. While the means may be manual it is preferably elastic to snap the head out of the recess automatically when the bow is flexed to unbrace. To return the head to the recess in bracing, the bow is preferably provided with elastic means having one end attached to the head and extending from the head toward the adjacent end of the bow to maintain the string taut when the bow is unbraced. In the preferred embodiment the ejecting means comprises a part settable to two positions in one of which the head is movable into the recess when the bow is braced and in the other of which the head is ejected from the recess in unbracing the bow. While the ejecting means may comprise any kind of an elastic part, such as an elastic cord, spiral tension spring, or rubber band, it preferably comprises a leaf spring movable between two positions in one of which it is retained in retracted position to permit the head to enter the recess when the bow is braced and in the other of which it snaps the head out of the recess in unbracing the bow.

For the purpose of illustration typical embodiments of the invention are shown in the accompanying drawings in which—

Fig. 1 is a side elevation of a bow;

Fig. 2 is a central section of one end of the bow when braced and with the ejector latched in retracted position;

Fig. 3 is a similar view with the ejector unlatched;

Fig. 4 is a similar view showing the head being ejected in unbracing the bow;

Fig. 5 is a similar view showing the bow in unbraced condition;

Fig. 6 is a similar view showing the ejector latched again preparatory to bracing the bow;

Fig. 7 is a view from the line 7—7 of Fig. 2;

Fig. 8 is a section on line 8—8 of Fig. 7;

Fig. 9 is a rear view of the ejector;

Fig. 10 is a rear view of the lower end of the bow;

Fig. 11 is a rear view of one end of a modified bow; and

Fig. 12 is a section on line 12—12 of Fig. 11.

While the present invention is applicable to bows of many types it is illustrated as applied to a bow of the type shown in Fig. 1 in which the bow is indicated at 1 and the string at 2. As shown in the other figures the rear face of the bow (commonly called the "face") is provided with a recess 3 extending transversely from side to side. Extending from the center of this recess toward the opposite end of the bow is a groove 4 to accommo-

2

date the string when the bow is braced. Seated in the recess 3 is an elongate cylindrical head 6 to the center of which the string 2 is attached. Extending from the recess 3 to the rear face of the bow is a mouth 7 through which the head 6 may be removed from the recess when tension on the string 2 is relieved in unbracing the bow. As shown in Figs. 2 to 6 the recess slopes upwardly toward the rear face of the bow so that there is no tendency of the head 6 to slip out of the recess when the bow is braced.

The end of the bow is provided with a groove 8. An elastic cord 11 extends through the groove with one end fastened to the center of the head 6 and the other end fastened to the front of the bow (commonly called the "back") at 12. A tubular guard 13 may be disposed over the lower end of the cord.

As shown at 14 the bottom of the groove 4 is widened so that the groove is T-shaped in cross-section. Slidable lengthwise of the groove 4 is a leaf spring 16 (Fig. 9). The lower end of the spring is provided with a slot 17 to receive a screw 18 so that the spring may slide from the lower position shown in Figs. 2, 6 and 7 to the upper position shown in Figs. 3, 4 and 5. The lateral portions 14 of the groove 4 increase in thickness toward the recess 7 so that the spring 16 may flex from the position shown in Figs. 2, 3 and 6 to the position shown in Figs. 4 and 5. The upper end of the spring has a forwardly curving end 19 which is widened to provide shoulders 21 and which is bifurcated to provide a slot 22. At the upper forward corners of the lateral portions 14 of the slot 4 the bow is provided with recesses 23 to receive the shoulders 21 when the spring is moved to lower position, thereby to hold the spring in the retracted position shown in Figs. 2, 3 and 6. When the spring is moved to its upper position it is free to spring rearwardly to the position shown in Figs. 4 and 5.

To unbrace the bow the spring is moved to the upper position shown in Fig. 3 where it is free to spring forwardly when the head 6 is lifted out of the recess 3. Then when the bow is flexed in the usual way the spring snaps from the position shown in Fig. 3 to the position shown in Fig. 4, thereby ejecting the head 6 from the recess 3. When the bow is permitted to straighten again the head slides down the rear face of the bow to the position shown in Fig. 5. This increases the tension in the elastic cord 11 to hold the string taut while the bow is unbraced. To brace the bow the upper end of the spring 16 is pushed forwardly and the spring is moved downwardly until the shoulders 21 seat in the recesses 23, at which time the parts are in the positions shown in Fig. 6. Then when the bow is flexed in bracing the elastic cord 11 pulls the head 6 from the position shown in Fig. 6 back to the position shown in Fig. 2, the head snapping back into the recess because the spring 16 is latched in retracted position.

Instead of using a cylindrical head 6 as shown in Figs. 2 to 8, the head may have any other desired shape. For example a ball-shaped head 26 is illustrated in Fig. 10 to anchor the string in the lower end of the bow. At this end of the bow the slot 27 extending from the head recess 28 to the rear face of the bow is preferably narrower than the head 26 so that the head can be removed from the recess only by lateral movement along the recess to one side of the bow after the string 2 has been lifted out of the groove 29. Thus the danger of the head becoming displaced from the recess accidentally in bracing and unbracing the bow is greatly reduced.

The modification shown in Figs. 11 and 12 differs from the aforesaid illustration in the addition of a pulley 31 in the groove 8 to reduce the friction on the elastic part 11 and the omission of the slot 17 and screw 15, the

spring being slidably held in the groove merely by friction.

It should be understood that the present disclosure is for the purpose of illustration only and that this invention includes all modifications and equivalents which fall within the scope of the appended claims.

I claim:

1. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and means to eject the head from the recess when tension in the string is relieved.

2. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and elastic means to snap the head out of the recess when tension in the string is relieved.

3. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, elastic means attached to the bow and head and extending from the head toward the adjacent end of the bow in alignment with said groove to maintain the string taut when the bow is unbraced, and means to eject the head from the recess when tension in the string is relieved.

4. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, elastic means attached to the bow and head and extending from the head toward the adjacent end of the bow in alignment with said groove to maintain the string taut when the bow is unbraced, and elastic means to snap the head out of the recess when tension in the string is relieved.

5. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and means for controlling the movement of the head into and out of the recess, said means having a part settable to two positions in one of which the head is movable into the recess when the bow is braced and in the other of which the head is ejected from the recess when tension in the string is relieved.

6. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and elastic means attached to the bow and head and extending from the head toward the adjacent end of the bow in alignment with said groove to maintain the string taut when the bow is unbraced, and elastic means to snap the head out of the recess when tension in the string is relieved.

head so that the head cannot pull out through the groove when the bow is braced, the mouth of the recess being larger than the head, elastic means attached to the bow and head and extending from the head toward the adjacent end of the bow in alignment with said groove to maintain the string taut when the bow is unbraced, and means for controlling the movement of the head into and out of the recess, said means having a part settable to two positions in one of which the head is movable into the recess when the bow is braced and in the other of which the head is ejected from the recess when tension in the string is relieved.

7. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, elastic means having one end attached to the head and extending from the head toward the adjacent end of the bow in alignment with said groove and thence over a guide at said end and along the back of the bow to maintain the string taut when the bow is unbraced, and means for controlling the movement of the head into and out of the recess, said means having a part settable to two positions in one of which the head is movable into the recess when the bow is braced and in the other of which the head is ejected from the recess when tension in the string is relieved.

8. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and a leaf spring to snap the head out of the recess when tension in the string is relieved.

9. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, elastic means attached to the bow and head and extending from the head toward the adjacent end of the bow in alignment with said groove to maintain the string taut when the bow is unbraced, and a leaf spring to snap the head out of the recess when tension in the string is relieved.

10. An archery bow characterized in that the string has a head on one end which is wider than the string, one end of the bow has a recess in its face to receive the head and a groove leading from the recess toward the other end of the bow along the face of the bow to receive the string, the groove being narrower than the head so that the head cannot pull out through the groove when the bow is braced, the mouth of the recess being larger than the head, and means for controlling the movement of the head into and out of the recess, said means including a leaf spring settable in two positions in one of which it is retained in retracted position to permit the head to enter the recess when the bow is braced and in the other of which it snaps the head out of the recess when tension in the string is relieved.

11. An archery bow characterized in that the string has a head on one end which is wider than the string, one end of the bow has a recess in its face to receive the head and a groove leading from the recess toward the other end of the bow along the face of the bow to receive

the string, the groove being narrower than the head so that the head cannot pull out through the groove when the bow is braced, the mouth of the recess being larger than the head, elastic means attached to the bow and head and extending from the head toward the adjacent 5 end of the bow in alignment with said groove to maintain the string taut when the bow is unbraced, and means for controlling the movement of the head into and out of the recess, said means including a leaf spring settable in two positions in one of which it is retained in retracted position to permit the head to enter the recess when the bow is braced and in the other of which it snaps the head out of the recess when tension in the string is relieved. 10
